(57) **CLAIM**

The ornamental design for an electronic device, as shown and described.

DESCRIPTION

FIG. 1 is a perspective view of an electronic device, showing my new design;

FIG. 2 is as partial, enlarged view of a portion of FIG. 1 thereof;

FIG. 3 is a front view thereof;

FIG. 4 is a top view thereof;

FIG. 5 is a right-side view thereof;

FIG. 6 is a left-side view thereof;

FIG. 7 is a rear view thereof; and,

FIG. 8 is a rear view of the electronic device in an alternate configuration.

The broken lines depict environmental subject matter only and form no part of the claimed design. A bottom view of the electronic device is not shown because it depicts environmental subject matter only, and forms no part of the claimed design.
